US0D1054642S

(12) **United States Design Patent** (10) Patent No.: **US D1,054,642 S**
(45) Date of Patent: ** Dec. 17, 2024

(54) **AUTOMATIC SWIMMING POOL CLEANER**

(71) Applicant: **XINGMAI INNOVATION
TECHNOLOGY (SUZHOU) CO.,
LTD.**, Suzhou (CN)

(72) Inventor: **Shilei Zhang**, Jiangsu (CN)

(**) Term: **15 Years**

(21) Appl. No.: **35/518,270**

(22) Filed: **Jul. 25, 2023**

(80) **Hague Agreement Data**

Int. Filing Date: **Jul. 25, 2023**

Int. Reg. No.: **DM/231085**

Int. Reg. Date: **Jul. 25, 2023**

Int. Reg. Pub. Date: **Sep. 8, 2023**

(30) **Foreign Application Priority Data**

Mar. 31, 2023 (CN) 202330169681.4

(51) **LOC (14) Cl. 15-05**

(52) **U.S. Cl.**

Primary Examiner — John R Yeh

(57) **CLAIM**

The ornamental design for an automatic swimming pool cleaner as shown and described.

DESCRIPTION

1.1: Front

1.2: Back

1.3: Left

1.4: Right

1.5: Top

1.6: Bottom

1.7: Perspective

1.8: Perspective

1.9: Perspective

The broken lines in the figures show other parts of the automatic swimming pool cleaner that do not form part of the claimed design.

1 Claim, 9 Drawing Sheets
